(57) **CLAIM**

The ornamental design for a table with attached seat, as shown and described.

DESCRIPTION

FIG. 1 is a perspective view of the table with attached seat of my invention;

FIG. 2 is a left side elevational view thereof, the right side elevational view being a mirror image thereof;

FIG. 3 is a top plan view thereof;

FIG. 4 is a bottom plan view thereof, the elements shown in phantom view are environmental material not forming a part of the claimed design;

FIG. 5 is a front elevational view thereof; and,

FIG. 6 is a rear elevational view thereof.
